UNITED STATES PATENT OFFICE.

RAYMOND W. BURNS, OF POUGHKEEPSIE, NEW YORK, ASSIGNOR TO JAMES L. TAYLOR
MFG. CO., A CORPORATION OF NEW YORK.

CLAMP.

Application filed November 9, 1922. Serial No. 599,782.

To all whom it may concern:

Be it known that I, RAYMOND W. BURNS, a citizen of the United States, and a resident of Poughkeepsie, in the county of 5 Dutchess and State of New York, have invented new and useful Improvements in Clamps, of which the following is a specification.

This invention relates to bar clamps, such 10 as are adapted to be used in clamp machines, and I have shown the invention applied to one of the clamps of a clamp machine, although I desire it to be understood that the invention can be applied to any 15 bar clamp. More particularly the present invention relates to improvements in the clamp shown in my co-pending application Serial No. 599,781, filed Nov. 9, 1922, for clamping stock flatwise or on edge, as in 20 veneering, and for clamping thick stock, such a clamp having upper and lower clamping means and connecting strips.

The objects of the present improvements are to provide improved means of access 25 to such a clamp for inserting or removing work; to avoid taking off the upper clamping means, and the consequent liability of mislaying or losing it; to enable the upper clamping means to be swung out of the way 30 for the removal and insertion of work; to secure such swinging in a vertical direction; to provide for such swinging automatically; to hingedly connect said clamping means to the rear or adjustable jaw; to provide 35 means for releasably connecting it to the front or fixed head; to secure such pivoting without interfering with the longitudinal adjustment of the clamp for different widths 40 of work; to pivot the connecting strip upon the same latch which secures it to the head; to secure means for automatically locking the hinged connecting strip in closed position by clamping the work, and to obtain other advantages and results as may be 45 brought out in the following description.

Referring to the accompanying drawings, in which like numerals of reference indicate the same parts throughout the several views,

Figure 1 is a perspective view of a clamp 50 machine clamp constructed in accordance with the invention;

Figure 2 is a side elevation of the same in central vertical longitudinal section, except at its attaching end;

Figure 3 is a side elevation of the adjustable jaw and related parts;

Figure 4 is a plan of the same;

Figure 5 is a plan of the fixed jaw;

Figure 6 is a view on line 6—6 of Fig. 5, looking in the direction indicated by the arrow, and

Figure 7 is a perspective view of the lower portion of the head from the rear, with one of the bars secured thereto.

In the specific embodiment of the invention illustrated in said drawings, 1 indicates a spanner foot which is disposed transversely of the clamp and extended upwardly from the same to provide a bearing 2 for a cross-rod 3 of a clamp carrier and also extended downwardly from the clamp to provide a fork 4 to receive another cross-rod 5. I have for convenience shown said spanner foot as a means for connecting the longitudinal angle bars 6, 6 of the clamp, 65 although it will be understood that any other suitable and well-known form of foot or means for joining the ends of said angle bars or holding them in fixed relation to each other, may be employed without departing from the spirit and scope of the 70 invention.

The angle bars 6, 6 are also a specific form of bar which is for convenience used to illustrate my invention, and other well-known 75 forms of bars may be employed. The angle bars shown are arranged in parallel relation with two of their flanges vertical and adjacent and the other two horizontal and extending outwardly apart from each other 80 to form a work table, and at their ends away from the spanner foot 1 the bars 6, 6 are secured to a head 7, as by being riveted thereto by their vertical flanges and also by their 85 horizontal flanges, as clearly shown in Figures 1 and 2. The portion of this head 7 which lies between the bars spaces them the same as the foot 1, and that portion of the head which overlies the upper surface of the bars is wider and forms an upwardly projecting fixed jaw 8 against which the work 90 is adapted to lie. The lower part of the 95

head between the bars 6, 6 is apertured longitudinally of the same, see Figure 2, said aperture being enlarged as at 9 to receive a rotatable nut 10 which has a handle 11 at its front projecting end for turning and is provided adjacent the head with an annular flange 12 to be engaged by a retaining member 13 to prevent longitudinal movement of the nut, while permitting such free rotation. The threaded end 14 of a connecting strip 15 enters said nut 10, said strip extending between the bars 6, 6 toward the foot 1 and serving to engage an adjustable jaw 16 to clamp the same toward the fixed jaw 8. Preferably the rearwardly extending portion of the head 7 forms wings 17, 18 at opposite edges of the horizontally disposed strip 15, and said wings and the portion of the aperture of the head through which the connecting strip extends are provided with recessed guideways 91, 91 for the edges thereof, to prevent it turning out of horizontal plane, the said guideways being best shown in Figure 7 of the drawings.

25 The adjustable jaw 16 seats slidably upon the work supporting surfaces of the bars 6, 6 and preferably has at its opposite edges projections 18 which extend over and beneath said edges; the jaw also has arms 19, 19 extending downwardly between the bars 6, 6 adjacent thereto and connected at their lower ends by a cross-piece 20 which underlies said bars 6, 6, said arms also having another cross-piece 21 higher up between themselves which supports the connecting strip 15, see Figure 2. A bell-crank latch 22 mounted upon the adjustable jaw 16 to swing vertically normally has one of its arms 23 projected into one of a series of apertures 24 in the connecting strip 15 by a spring 25, as said aperture lies above the upper cross-piece 21, to connect the adjustable jaw to said connecting strip; at the same time this connection can be released by swinging the latch 22 to withdraw its arm 23 from the aperture 24, and thus the adjustable jaw set wherever desired for clamping purposes.

50 The construction thus far described corresponds in a general way to that shown in my co-pending application Serial No. 599,781, filed November 9, 1922, but in the construction of that application the means for clamping the tops of the fixed and adjustable jaws toward each other could be removed for putting in or taking out work only by withdrawing it longitudinally. In the present application a construction is provided by which the upper clamping means is hinged to one jaw, preferably the rear or adjustable jaw, and releasably engages the other jaw for clamping, so that more convenient access for the work is provided. Describing this feature of the improved clamp, it will be noted that the adjustable jaw 16 has at its top posts 26, 27, Figure 1, which

project upwardly and are preferably connected at their tops, as at 28; these posts are spaced transversely of the clamp to provide a slideway for a connecting strip 29, and also they are spaced longitudinally of the clamp so that a bell-crank finger latch 30 may be pivoted horizontally upon one of them, as 26, and normally swung by a spring 31 engaging its handle end 32 to force the other end 33 through one of a series of apertures 34 in the connecting strip 29 and into contact with the other post 27, all as shown in Figures 1, 3 and 4 of the drawings. The connecting strip 34 is preferably a duplicate of the connecting strip 15 and the locking end 33 of the latch 30 is in vertical alinement with the locking end 23 of the lower latch 22, so that when the latches are engaged in corresponding holes of the connecting strips and the connecting strips correspondingly drawn upon, the upper and lower ends of the adjustable jaw 16 will be correspondingly clamped against the work in a plane perpendicular to the work-engaging surfaces of the bars 6, 6.

At the upper end of the fixed jaw 8 is a grooved seat 35 extending longitudinally of the clamp and laterally open preferably at its side away from the bar to receive the threaded end portion 36 of the connecting strip 34, said grooved seat having a longitudinal guideway or slot 37 in its bottom to receive the edge of the connecting strip and hold the same against turning. The front end of the grooved seat is enlarged, as at 38, to receive a handled nut 39 adapted to screw onto the threaded end of the connecting strip and being provided with a flange 40 adapted to underlie ears 41, 41 at the front ends of the upper edges of the grooved seat.

It will be noted that the upper connecting strip 34 lies vertically edgewise instead of horizontally like the lower connecting strip 15, and the construction is such that when work is to be inserted or removed, this connecting strip 34 can swing upwardly upon the finger latch 30 as a pivot, the clamping nut 39 and forward threaded end 36 of the connecting strip moving freely upward out of their grooved seat. At the same time when the clamping nut 39 is returned to its seat and tightened to clamp the adjustable jaw 16 against a piece of work, its flange 40 underlies the ears 41, 41 so that it cannot escape upward.

Preferably means are provided for automatically swinging the upper connecting strip 34 upward for the insertion or removal of work, and I have shown such means as a sleeve 42 slidable upon the rear end of the connecting strip 34 and provided at its forward end with a lateral lug 43 by which it is pivoted to the post 27, the pivot 44 being in alinement with the end 33 of the finger latch 30 which enters the aper-

tures in the connecting strip, as clearly shown in Figure 4. Such pivoting of the sleeve 42 thus permits it to swing with the connecting strip 29, and the rear end of the sleeve is provided with an ear 45 to receive one end of a tension spring 46 the other end of which is connected to a suitable ear 47 at a lower point of the rear of the adjustable jaw 16. This spring 44, being brought under tension by seating the clamping nut 39, will serve to elevate the connecting strip as soon as the clamping nut is released so as to clear its ears 41, 41. The projections 18 upon the base of the adjustable jaw 15 which hook over the edges of the bars 6, 6, as before described, serve to prevent the weight of the upper connecting strip when elevated from unduly tilting the adjustable clamping jaw forward, and for this purpose 20 said projections are preferably located only at the rear of the base of said adjustable jaw, as shown.

At the same time, if it is desired to remove the upper clamping strip 29 entirely, it can be done by disengaging the latch 30, for the insertion of work or any other purpose. Then when the operator desires to replace said upper clamping strip he has only to push its rear end against the latch 30, which will allow said end to pass.

While I have shown and described one possible embodiment of the invention, it will be understood that this is only for the purpose of illustrating the principles of the invention and that many modifications and changes can be made in the detail construction without departing from the spirit and scope thereof. Therefore, I do not desire to be understood as restricting myself except as required by the following claims when construed in the light of the prior art.

Having thus described the invention, what I claim is:

1. In a bar clamp, the combination of two jaws adapted to oppositely engage a piece of work, and clamping means extending between the pairs of opposite ends of said jaws, one of said clamping means being hingedly connected to one of said jaws and adapted to detachably engage the other jaw.

2. In a clamp, the combination with a bar, jaws on said bar adapted to oppositely engage a piece of work, and means for clamping said jaws together at their ends next said bar, of means for clamping together the other ends of said jaws hingedly connected to one of said jaws and detachable from the other.

3. In a clamp, the combination with a bar, jaws on said bar adapted to oppositely engage a piece of work, and means for clamping said jaws together at their ends next said bar, of a connecting strip for clamping together the other ends of said

jaws arranged edgewise with respect to the bar, and pivot means detachably engaging said strip on one of the jaws.

4. In a clamp, the combination with a bar, jaws on said bar adapted to oppositely engage a piece of work, and means for clamping said jaws together at their ends next said bar, of an apertured connecting strip for the other ends of said jaws arranged edgewise with respect to the bar, and pivot means on one of said jaws adapted to be removably inserted in any one of said apertures.

5. In a clamp, the combination with a bar, jaws on said bar adapted to oppositely engage a piece of work, and means for clamping said jaws together at their ends next said bar, of posts on the top of one of said jaws, a connecting strip between said posts, means for pivoting said strip with respect to said posts, and means on the other jaw for drawing upon said connecting strip.

6. In a clamp, the combination with a bar, jaws on said bar adapted to oppositely engage a piece of work, and means for clamping said jaws together at their ends next said bar, of posts on the top of one of said jaws, an apertured connecting strip between said posts, and a latch fulcrumed on one of said posts and adapted to abut the other post through an aperture of the strip for pivoting said strip.

7. In a bar clamp, the combination of two jaws adapted to oppositely engage a piece of work, and clamping members extending between the pairs of opposite ends of said jaws, one of said clamping members being hingedly connected to one of said jaws and adapted to detachably engage the other jaw, and means for swinging said hinged clamping member into open position.

8. In a bar clamp, the combination of two jaws adapted to oppositely engage a piece of work, and clamping members extending between the pairs of opposite ends of said jaws, one of said clamping members being hingedly connected to one of said jaws and adapted to detachably engage the other jaw, a sleeve on said hinged clamping member, and means engaging said sleeve to swing the clamping member into open position.

9. In a bar clamp, the combination of two jaws adapted to oppositely engage a piece of work, and clamping members extending between the pairs of opposite ends of said jaws, one of said clamping members being hingedly connected to one of said jaws and adapted to detachably engage the other jaw, a sleeve on said hinged clamping member, and a spring engaging said sleeve to swing the clamping member into open position.

10. In a bar clamp, the combination of two jaws adapted to oppositely engage a piece of work, and clamping members extending between the pairs of opposite ends

of said jaws, one of said clamping members being hingedly connected to one of said jaws and adapted to detachably engage the other jaw, a pivoted sleeve on said hinged clamping member, and means engaging said sleeve to swing the clamping member into open position.

11. In a clamp, the combination with a bar, a fixed jaw and a movable jaw on said bar, and means for clamping said jaws together at their ends next said bar, of posts on the top of one of said jaws, a clamping member between said posts, means for pivoting said member with respect to said posts, a sleeve on said clamping member pivoted on the same line therewith, and means engaging said sleeve to swing the clamping member into open position.

12. In a clamp, the combination with a bar, a fixed jaw and a movable jaw on said bar, and means for clamping said jaws together at their ends next said bar, of posts on the top of one of said jaws, an apertured connecting strip between said posts, a latch fulcrumed on one of said posts and adapted to abut the other post through an aperture of the strip for pivoting said strip, a sleeve on said connecting strip pivoted to the last-mentioned post opposite the abutting end of the latch, and means engaging said sleeve to swing the connecting strip into open position.

13. In a bar clamp, the combination of a jaw projecting from the bar and having at

its end away from the bar a seat parallel thereto and open laterally, a clamping screw loose in said seat, a handled nut on said screw, a connecting strip extending rearward from said screw, a jaw adapted to be engaged by said strip, and means for locking said nut against lateral escape from said seat.

14. In a bar clamp, the combination of a jaw projecting from the bar and having at its end away from the bar a seat parallel thereto and open laterally, a clamping screw loose in said seat, a handled nut on said screw, a connecting strip extending rearward from said screw, a jaw adapted to be engaged by said strip, and means on said seat for automatically locking said nut against lateral escape therefrom when tightened in clamping.

15. In a bar clamp, the combination of a jaw projecting from the bar and having at its end away from the bar a seat parallel thereto and open at its side away from the bar, a clamping screw loose in said seat, a handled nut on said screw at the front of the head, a connecting strip extending rearward from said screw, and a second jaw adapted to be engaged by said strip, said seat having lugs at its forward end and said nut having a portion adapted to lie beneath said lugs when the nut is tightened in clamping and prevent lateral escape from the seat.

RAYMOND W. BURNS.
